UNITED STATES PATENT OFFICE.

WILLIAM H. SCOTT, OF MAPLEWOOD, MISSOURI, ASSIGNOR TO ELLIOT FROG & SWITCH COMPANY, OF EAST ST. LOUIS, ILLINOIS, A CORPORATION.

ADJUSTABLE SWITCH-ROD.

No. 813,920.

Specification of Letters Patent.

Patented Feb. 27, 1906.

Application filed December 23, 1905. Serial No. 293,098.

To all whom it may concern.

Be it known that I, WILLIAM H. SCOTT, a citizen of the United States, residing in Maplewood, in the county of St. Louis and State 5 of Missouri, have invented certain new and useful Improvements in Adjustable Switch-Rods, of which the following is a full, clear, and exact description, reference being had to the accompanying drawings, forming part of 10 this specification.

My invention relates to that class of adjustable switch-rods in which an eccentric is used for the purpose of securing adjustment of the rod relative to the switch-point rail-sections of a railway-switch or adjustment of 15 said switch-point rail-sections relative to the switch-rod.

Figure I is a cross-section of the main rails and switch-point rail-sections of a railway-track with my adjustable switch-rod shown connected to said switch-point rail-sections. Fig. II is an enlarged longitudinal section taken through one of the brackets connected to the switch-point rail-section, a portion of 20 the switch-rod, and the means for adjustably connecting these parts. Fig. III is an inverted plan view of the parts shown in Fig. II. Fig. IV is a fragmentary view of the switch-rod. Fig. V is a perspective view of the eccentric block that operates in the switch-rod. Fig. VI is a similar view to Fig. II, illustrating a modification. Fig. VII is an inverted plan view of the bracket used in the modification shown in Fig. VI.

35 A designates the main rails of a railway-track, and B the switch-point rail-sections that are adapted to be moved to said main rail.

1 designates a switch-rod that is located, 40 as usual, beneath the main track-rails for restriction in a direction transverse of the railway-track. This switch-rod is provided with a circular opening 2.

3 designates brackets that are secured to 45 the switch-point rail-sections B by suitable means, such as bolts, and each of which is provided with a U-shaped arm having an upper member 4 and a lower member 5, said members being spaced apart to permit of the 50 introduction of the switch-rod between them. Either of the brackets 3 may be connected to the switch-rod by my adjustable connection,

to be hereinafter described, or both of them may be so connected. I will, however, in the subsequent description refer to the connection as applying to only one of the brackets. 55

In the adjustment device, as illustrated in Figs. I to III, the upper member 4 of the U-shaped arm is provided with a circular bolt-hole 4', while the lower member 5 of said arm 60 is provided with a non-circular or polygonal bolt-hole 5'. This last-named or non-circular bolt-hole is preferably of star shape in outline for the purpose of providing for a greater degree of adjustment of the bolt 65 which fits therein and which will be herein-after mentioned and to provide at the same time sharper angular seats in which said bolt fits to be held from rotation.

6 designates an eccentric block (see Figs. 70 II and V) which is adapted to seat in the opening 2 in the switch-rod 1 and which is rendered of eccentric nature due to its being provided with a bolt-hole 7, offset from the axis of the block. Said bolt-hole is non-circular, being preferably square. 75

8 designates a bolt that is adapted to pass through the members 4 and 5 of the arm in the bracket 3 and through the eccentric block 6, that occupies a position between said 80 arms and in the switch-rod. The shank of this bolt is provided with a non-circular portion 9, located adjacent to the head of the bolt and adapted to seat in a circular bolt-hole 4' in the arm member 4, a polygonal portion 10, adapted to seat in the non-circular bolt-hole 7 in the eccentric block 6, and the non-circular opening 5' in the lower bracket-arm member 5. The shank of the bolt terminates in a threaded portion 11, which receives a nut 12, that is adapted to bear against the bracket-arm member 5. When the bolt 8 is introduced into the bracket-arm members, it is passed first through the circular bolt-hole 4' in the bracket-arm member 4 90 and its polygonal portion 10, then passes through the polygonal opening 7 in the eccentric block 6, and finally into the polygonal bolt-hole 5' in the bracket-arm member 5, in which the bolt when seated is prevented 95 from turning, due to the non-circular formation of the bolt shank portion 10 and said bolt-hole 5'. As a consequence of the bolt being held from rotation the eccentric block 6

100

is held in a fixed position within the aperture 2 of the switch-rod, and therefore the switch-rod is held from play relative to the bracket 3, attached to its rail point-section. When 5 it is desired to adjust the switch-rod, the nut 12 on the bolt 8 is removed or partially removed to permit of the partial withdrawal of said bolt in order that its polygonal shank portion 10 may be withdrawn from the polygonal bolt-hole in the bracket-arm member 5. The said polygonal bolt-hole portion of the bolt-shank at this time remains in the eccentric block, and by rotating the bolt the eccentric block is turned to any desired degree 15 to shift or adjust the switch-rod with respect to the bracket connected thereto. By this means the switch-point rail-sections are adjusted relative to each other.

In Figs. VI and VII, I have shown a modification in which the switch-rod 1^a and the eccentric block 6^a are of the same form as that previously described. In this construction the bracket 3^a has the upper and lower arm members 4^a and 5^a. Instead of producing 20 a circular bolt-hole in the upper arm member and a non-circular bolt-hole in the lower arm member I reverse the locations of these bolt-holes, thus providing the circular bolt-hole 5^b in the lower arm member and the 25 non-circular bolt-hole 4^b in the upper member. By so doing I provide for the introduction of the bolt 8 in an upward direction first through the lower bracket-arm member, then through the eccentric block, and lastly 30 through the upper bracket-arm member. As a consequence the non-circular shank portion 10^a of the bolt 8 is held from rotation by the upper arm member as distinguished from its being held by the lower arm member.

I claim as my invention—

1. In an adjustable switch-rod, the combination of a rod, an eccentric rotatably fitted in said rod, a bracket in which said rod is seated, and in a part of which is provided a non-circular bolt-hole, and a bolt passing 45 through said bracket and having a non-circular shank portion seating in said non-circular bolt-hole, substantially as set forth.

2. In an adjustable switch-rod, the combination of a rod, an eccentric rotatably fitted 50 in said rod, a bracket in which said rod is seated, and in a part of which is provided a star-shaped bolt-hole, and a bolt passing through said bracket and having a non-circular shank portion seating in said star-shaped 55 bolt-hole; said star-shaped bolt-hole having a number of seats in multiple of the corners of the shank portion of said bolt, substantially as set forth.

3. In an adjustable switch-rod, the combination of a rod, an eccentric rotatably seated in said rod and provided with a non-circular bolt-hole, a bracket having a pair of arm members between which said rod is seated, and a bolt passing through said bracket-arm 65 members, and having a non-circular shank portion; one of said bracket-arm members being provided with a circular bolt-hole and the other of said bracket-arm members being provided with a non-circular bolt-hole the 70 latter of which is adapted to receive the non-circular shank portion of said bolt, substantially as set forth.

WILLIAM H. SCOTT.

In presence of—

BLANCHE HOGAN,
H. G. COOK.
